(57) **CLAIM**

The ornamental design for a tank for work vehicle, as shown and described.

DESCRIPTION

FIG. 1 is a front, left perspective view of a tank for work vehicle according to our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front, right perspective view of a tank for work vehicle according to another embodiment of our new design, the front, rear, left side, right side elevational views and top and bottom plan views thereof being mirror images of FIGS. 2-7 and therefore not shown;

FIG. 9 is a front, left perspective view of a tank for work vehicle according to another embodiment of our new design; FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is a front, right perspective view of a tank for work vehicle according to another embodiment of our new design, the front, rear, left side, right side elevational views and top and bottom plan views thereof being mirror images of FIGS. 10-15 and therefore not shown;

FIG. 17 is a front, left perspective view of a tank for work vehicle according to another embodiment of our new design; FIG. 18 is a front elevational view thereof;

FIG. 19 is a rear elevational view thereof;

FIG. 20 is a left side elevational view thereof;

FIG. 21 is a right side elevational view thereof;

FIG. 22 is a top plan view thereof; and,

FIG. 23 is a bottom plan view thereof.

The dashed lines in the figures depict environment subject matter that forms no part of the claimed design.
